UNITED STATES PATENT OFFICE.

JOSEPHINE P. AYMER, OF DENVER, COLORADO.

LINGERIE CLASP.

Application filed October 6, 1925. Serial No. 60,783.

This invention relates to improvements in lingerie clasps and has for its object the production of a simple convenient and neat clasp that can be attached to the inside of the dress directly above the shoulder and through which the shoulder straps of the lingerie may pass.

It is well known among women that the shoulder straps of their lingerie have a tendency to slide out over the shoulders and down onto the arms where they become visible if sleeveless dresses are worn and cause more or less annoyance to the wearer.

It is apparent that if the shoulder straps could be fastened to the inside of the shoulder portion of the dress, they could not slide outwardly. If such fastening is accomplished by means of pins there can be no relative movement of the straps and the dress which is highly unsatisfactory. In order to get the most satisfactory results, the strap should be able to move with respect to the dress in the direction of its length, but be prevented from moving outwardly over the shoulder. I have found that if a metal clasp is sewed to the inside of the dress directly over the shoulder and the strap introduced into the clasp, it will be held from outward movement but will still be free to move longitudinally.

My invention relates to the construction of the clasp which I will now proceed to describe in detail, reference for this purpose being had to the accompanying drawing in which the preferred embodiment has been illustrated and in which:

Fig. 1 is a view showing the clasp in position on the wearer's dress and the shoulder strap in place thereon;

Fig. 2 is a perspective view of the clasp;

Fig. 3 is a view similar to that in Fig. 2 but with a portion of the upper side removed so as to more clearly disclose the construction;

Fig. 4 is a sectional view to an enlarged scale taken on line 4—4, Fig. 3;

Figs. 5 and 6 are details showing a slightly modified construction.

Numeral 1 indicates the shoulder portion of a lady's dress and 2 the shoulder strap that supports the lingerie, while 3 indicates the clasp that is secured to the inside of the dress directly over the shoulder. The clasp has been shown with considerable particularity in Figs. 2, 3 and 4 in which numeral 4 represents that portion that is fastened to

the dress and which will be referred to as the base. This base portion is provided with four or more holes 5 through which the thread is passed in securing the clasp to the dress. The end 6 is preferably rounded so as not to present any sharp corners or edges. Near the end 6 I have provided two upwardly spaced lugs that are preferably formed by pressing upwardly a portion of the metal in the manner indicated in Fig. 4. When these lugs are formed in this way the metal can be more economically used than if the lugs were formed by ears bent upwardly, from a blank formed in the manner indicated in Fig. 5, into the position shown in Fig. 6. The clasp is formed from a single piece of thin metal and has a top member 9 that is integral with the base and joined to the latter by a curved portion 10. Member 9 is bent downwardly near its end in the manner indicated by numeral 11 and the extreme outer end 12 is bent upwardly and away from the base 3. The convex or lower side of the curved portion 11 contacts with the upper surface of the base directly between the lugs 7 and is of such width that it fits between these lugs. When the clasp is formed it is bent so that the curved part 11 presses against the base 4 with some force. The clasp is secured to the dress by thread that passes through the holes 5 and the strap 2 is inserted into the opening 13 by being passed between the base and the curved part 11. The lugs that project upwardly from the base at each side of the curved part 11 act as stops and prevent the strap from being withdrawn. The strap 2 can be easily put into place by separating the ends 6 and 12 a short distance and then introducing the strap thereinto.

The clasp can be made of thin light metal that will not annoy the wearer in any way and will still be suitable for the purpose.

The clasp has been so designed that it can be formed by dies and can therefore be stamped and bent into shape by machinery.

In the drawing the several figures are shown to an enlarged scale so as to make it possible to more clearly illustrate the construction, the actual article being made of thinner and narrower material.

Having now described the invention what is claimed as new is:

A lingerie clasp consisting of a piece of thin metal bent intermediate its extremities to form a U-shaped structure whose adjacent

cooperating members are parallel and spaced a short distance apart, one of said members being provided with a lug on each side near its end said lugs being struck up out of the metal of said member and spaced apart, the other member being provided near its end with a transverse part adapted to contact

with the adjacent surface of the cooperating member, the member having the lugs being constructed to facilitate its attachment to a ¹⁰ garment for the purpose set forth.

In testimony whereof I affix my signature.

JOSEPHINE P. AYMER.
